CLAIM

The ornamental design for a multi-lancet lancing device, substantially as shown and described.

DESCRIPTION

FIG. 1 is a perspective view of a multi-lancet lancing device of the present invention.

FIG. 2 is a bottom view thereof.

FIG. 3 is a top plan view thereof.

FIG. 4 is a right side view thereof.

FIG. 5 is a left side view thereof.

FIG. 6 is a front elevational view thereof; and,

FIG. 7 is a rear elevational view thereof.

The broken lines in various of the figures are for illustrative purposes only and form no part of the claimed design.
